UNITED STATES PATENT OFFICE.

MEYER J. LIEBERMAN, OF BALTIMORE, MARYLAND.

KNICKERBOCKER-KNEE.

1,113,662.

Specification of Letters Patent.

Patented Oct. 13, 1914.

Application filed March 28, 1913. Serial No. 757,300.

To all whom it may concern:

Be it known that I, MEYER J. LIEBERMAN, a citizen of the United States of America, residing at Baltimore and Diamond streets, 5 Baltimore, Maryland, have invented certain new and useful Improvements in Knickerbocker-Knees, of which the following is a specification.

This invention relates to wearing apparel, 10 particularly to a knee-band tension and adjusting device for knickerbockers. Various devices having this function have been produced and patented and the object of the present invention is to evolve an improved 15 arrangement as compared with those known to the prior art.

Of the various devices which have been patented, all of those which are related to the present one have the knee portion of the 20 trousers or knickerbockers slotted and a strap is secured to the bottom edge of the trousers. This overlaps the slot and a buckle is used to fasten the strap and adjust its length, to change the circumference of 25 the trousers' knee and the tension of the same about the limb of the wearer. If the strap is not adjustable, it is made of elastic material and in some instances it is both adjustable and elastic.

30 The objection to the non-elastic adjustment as used alone, is obvious, as the discomfort of a tight band which can be stretched but little, if at all, is apparent; also the strap soon becomes worn. If the 35 band is made of elastic material and adapted to stretch sufficiently to accommodate the wearer without adjustment of the strap, it is found that the wide inside flap which must be used to close the slot, becomes 40 wrinkled or wadded as the band is expanded or contracted, so that it not only does not perform the function for which it is intended, but causes a considerable amount of discomfort to the wearer. To overcome

45 these various difficulties, I slot the trousers at two points, preferably on the inside and on the outside of the leg. At one side, generally on the outside, I use a non-elastic strap, conveniently forming an extension of 50 the knee-band of the trousers and any suitable means, as two or more buttons, is used to secure the strap at different points to the opposite side of the slot or vent, so that the knee-band is conveniently buttoned to fit 55 approximately the wearer's leg. Preferably in normal position, the sides of the slot over-

lap but slightly, but they may be overlapped to a considerable extent, the strap side overlying the other, but as the strap is non-elastic, the inside portion or flap, when once 60 laid flat, does not become wrinkled or wadded. To cause the knee-band to hug the limb and prevent it from slipping down when fastened, I insert an elastic member in the band as hereinafter described. At 65 the other slot F preferably provide two flaps which normally overlap and the knee-band is secured to the bottom edge of each flap. The knee-band on the side of the outer flap is opened to form a flat tube. An elastic 70 strap is inserted in the tube and secured therein at its inner end. The other end of the strap is secured to the knee-band on the outer face of the inside flap some distance back from the edge. The flaps so arranged 75 permit free contraction and expansion of the strap without wrinkling of either flap, and at the same time the flaps are so placed as to always close the slot. The non-elastic strap with the buttons provides sufficient variation 80 in the circumference of the knee so that it can be buttoned to fit the wearer approximately, and the elastic strap takes up the slack and causes the band to hug the knee when buttoned at a convenient tension. 85

A portion of a pair of knickerbockers to which the device of my invention has been applied, is illustrated in the accompanying drawing.

Figure I is a fragmentary side elevation 90 of the knee portion of the garment looking from the outside, both slots being open and having the flaps turned up for the purpose of illustration. Fig. II is a bottom plan of the knee portion of one leg. Fig. III is a 95 fragmentary, horizontal section through the pocket or tube showing the elastic band or strap and its relation to the flaps.

Referring to the drawings by reference numerals: The trousers' leg 1 is slotted or 100 provided with vents on the outer side at 2 and on the inner side at 3. The entire bottom edge of the trousers is preferably bound or encircled by the knee-band 4 which is discontinued at the slots 2 and 3, except at the 105 outer edge of the slot 2, where the band is extended, forming a non-elastic strap 5. This strap as shown, is pierced by two buttonholes 6 and 7 and on the other or inside slot, are buttons 8 and 18 secured to the 110 outer side of the band and spaced back in this instance by a considerable distance from

the edge of the slot. In normal position, *i. e.*, when the end buttonhole 6 engages the button 8, the edges of the slot overlap but slightly. However, when the strap is drawn up so that the buttonhole 7 engages the button 18, the outer flap is drawn over to a considerable extent, as two and one-half or three inches. The other slot, *i. e.*, that on the inside of the leg, is provided with a flap 10 on each side, the inside flap being numbered 9 in Fig. I, and the outside flap 10. The knee-band at the bottom of the latter flap is left open to form a tube 11; and an elastic strap 12 is inserted therein, being secured at its inner end at 13. The end of the strap projects from the tube and is secured to the knee-band at 14 on the opposite side of the slot, so that when the elastic strap is contracted, there being no tension placed upon it, the outside flap is not wrinkled or gathered and it overlaps the inside flap by a considerable margin, as an inch or more.

In the operation of the device, it will be apparent that the inside flap 15 of the outside slot may be laid flat and the end of the strap 5, drawn tight and secured by means of the button 8 or 18, either buttonhole 6 or 7 being utilized. As there is no contraction or expansion at this point and consequently no slipping of the flap 15 relatively to the knee or limb of the wearer, there is no tendency of this flap to wrinkle or become wadded; at the same time an efficient major adjustment is provided.

In regard to the slot 3 on the other side of the trousers' leg, the two flaps 9 and 10 overlap at this point. The flap 9 being inside and stationary, has no tendency to wrinkle if it is laid flat when the garment is first adjusted. The position of the elastic band 12 inside the tube 11 of the outside flap 10, tends to prevent that flap from wrinkling while its edge moves back and forth toward and from the point 14 of the flap 9, at which the end of the elastic band 12 is fastened. The operation of this portion of the device, *i. e.*, slot 3, flaps 9 and 10 and the elastic band 12—is to give a minor adjustment and

to cause the knee to contract and expand to conform to the motions of the wearer and 50 the consequent changes of configuration of the knee.

I have thus described specifically a single embodiment of my invention in order that its nature and operation may be clearly 55 understood. I do not desire however, to limit myself to all the details described, and the specific terms herein are used in their descriptive rather than their limited sense; the scope of the invention is defined in the 60 claims.

I claim—

1. Knickerbocker leg having at the knee two vertical slotted openings, one on each side, a non-elastic strap secured to one side 65 of one slot and normally overlapping the other side, means for securing the strap to the other side of the slot in various positions to provide for adjustment to the size of the knee, the other slot having overlapping flaps 70 one on each side of the opening, a tube in the outer flap, and an elastic band therein, fastened at its inner end in the tube, and at its outer end, to the flap on the other side of the slot at a point spaced back from the edge. 75

2: A knickerbocker having at each knee two vents, one on each side, having normally overlapping edges, a strap secured to the outer edge of one vent and overlapping the other edge, means for securing the strap and 80 adjusting it to vary the circumference of the knee opening, and an elastic strap secured at its respective ends to the opposite sides of the other opening.

3. A knickerbocker knee having two vents, 85 a non-elastic strap at one vent and means for adjusting it to vary the circumference of the knee, and an elastic strap at the other vent to maintain the tension of the garment at the knee. 90

Signed by me at Baltimore city, Maryland, this 27th day of March 1913.

MEYER J. LIEBERMAN.
